UNITED STATES PATENT OFFICE.

JULIUS KINDERVATER, OF RICHMOND, VIRGINIA.

BOILER.

No. 910,133.

Specification of Letters Patent.

Patented Jan. 19, 1909.

Application filed November 15, 1907. Serial No. 402,239.

To all whom it may concern:

Be it known that I, JULIUS KINDERVATER, a citizen of the United States, residing at Richmond, in the county of Henrico and 5 State of Virginia, have invented certain new and useful Improvements in Boilers, of which the following is a specification.

My invention relates to boilers, and more particularly to boilers designed for use on 10 locomotives. As is well known, boilers of the type usually employed for this purpose are of comparatively low efficiency, owing chiefly to the fact that they have a relatively small heating surface, such surface being 15 composed wholly of the fire box and fire tubes.

The primary object of my invention is, therefore, to provide a boiler of the locomotive type, which shall have a larger heating 20 surface, and, hence, a higher efficiency than those heretofore employed.

A further object of the invention is to provide this increased heating surface without increasing the external dimensions, or altering 25 the standard shape of the boiler, whereby my improved boiler may be mounted on any well known form of locomotive, substantially without change.

A further object is to provide a boiler 30 which can be constructed more easily and cheaply than the types now in use, and in which the cost of maintenance will be reduced.

A further object is to provide a structure 35 in which the use of stay-bolts is largely eliminated.

A further object is to provide a structure, by the use of which the emission of cinders from the smoke stack is greatly reduced. 40 This is due to the fact that the increased heating surface renders excessive draft unnecessary, and this also results in increasing the life of the boiler tubes.

With the above and other objects in view, 45 and to improve generally upon the details of such devices, my invention consists in the construction and arrangement of parts hereinafter described, and illustrated in the accompanying drawings, in which:—

50 Figure 1 is a central, longitudinal section, through my improved boiler and firebox, the grate being omitted for clearness. Fig. 2 is a view of the same partly in end elevation, and partly in transverse section along the line 2—2, Fig. 1. Fig. 3 is a plan of 55 the lower water drum, parts being shown

in section. Fig. 4 is an enlarged sectional detail, substantially on the line 4—4 of Fig. 2, showing method of securing drum heads. Fig. 5 is a sectional view, on a greatly enlarged scale, showing certain details of construction hereinafter referred to. Fig. 6 is a section on line 6—6, of Fig. 5, looking in the direction of the arrow. Fig. 7 is a section of the tubes, taken on line 7—7, of Fig. 65 5. Fig. 8 is a cross sectional view of the sealing strip employed.

My invention contemplates, broadly, the provision of a combined water-tube and fire-tube boiler, and to this end I arrange water-tubes within the fire box, as now to be described.

Referring to the drawings in detail: 1 indicates the usual boiler shell, having the combustion chamber 2, and fire tubes 3, extending therefrom. The rear sheet 4, is carried downward to form the front wall of the forward waterleg, while the rear wall comprises a sheet 5, bent over on the sheet 4, and flanged internally to form the mouth of 80 the combustion chamber. The rear waterleg is formed by the usual mud ring 6^a, and sheets 6 and 7, bent and lapped as at 8, to form a fuel opening. All of said sheets are secured by means of the usual rivets, (not 85 shown).

Extending between the front and rear water legs are a pair of upper drums, 9, and a pair of lower drums, 10. By reference to Fig. 2, it will be seen that the upper drums 90 are larger than the lower, and are disposed relatively close together, while the lower drums are located at the extreme sides of the boiler. This arrangement is preferable, as it permits of great width of fire-box 95 between the lower drums, and at the same time, produces a structure which conforms to the standard shape of the locomotive type of boiler. The method of connecting these drums with the water legs, I regard as an 100 important feature of my invention. The rear sheet 5 of the front water leg is cut and turned up so as to form flanges 11, and 12, which embrace the ends of the upper and lower drums, respectively, and to which the 105 same are securely riveted. This is clearly shown in Fig. 3. The sheets 6 and 7, forming the rear water leg, are provided with pairs of similar out-turned flanges, 13, 15, 14 and 16, respectively, and the drums pass 110 entirely through this rear water leg, and terminate substantially flush with the outer

edge of the flanges 14, 16, as shown in Fig. 3. By reference to this figure also, as well as to Fig. 1, it will be seen that in that portion of the drums lying between the sheets 6 and 7 within the water leg, I form a series of large openings, 17, extending all around the drums, and serving, as is obvious, to establish communication between said drums and said water leg. Within the rear end of each of the drums, (as 9, Fig. 4) I fit a flanged ring 18, and secure the same in place by means of a series of rivets, 21, passing through said flange, the flange, 14, and the intervening drum 9. To this ring, 18, I then secure a removable head, 19, as by means of bolts, 20. This head, therefore, when removed, forms a convenient man-hole, through which ready access may be had for inspection or repairs. The two upper drums are united at frequent intervals throughout their length by means of a series of short water tubes, 22, over which is placed a layer of fire brick, 23, or other heat resisting material.

Extending between each upper drum and its corresponding lower drum, I arrange a series of water tubes, 24, beaded into the drums. I preferably dispose these tubes in rows, (three being shown) and the tubes of the inner rows may, or may not have their ends swaged or reduced, as found desirable. Although they are so shown in the drawing, it is to be understood that I do not wish to be limited to this construction. It is, however, desirable, that the tubes of the outer row should lie as close together as possible. To this end, therefore, I taper or swage the ends of these tubes from, say, $2\frac{1}{8}$ inches to $2\frac{1}{4}$ inches, or any suitable amount, and also place the outer holes, 26, in the drum very much closer together than the inner holes, 27. (See Fig. 3.)

It will now be understood that I propose to utilize the space between the two outer rows of tubes as the fire-box, and have these outer tubes constitute the side walls thereof. Hence, I space the tubes in the inner rows well apart, so that the heated products of combustion may readily circulate between them, but the tubes of the outer rows I arrange so that there is only a very small opening between them.

As to the method of arranging the outer rows of tubes and associated parts, reference is had to Figs. 5, 6, 7 and 8. Of these, Fig. 5 is a view looking from the outside of the boiler, and shows a fragment of one of the drums, 10, at one end, where it enters one of the water legs, say, for instance, where it is secured to sheet 5 of the forward water leg. The construction of both ends of all the drums is the same, so that a description of this one will suffice. The drawing clearly shows the ends of the outer row of tubes, 24, swaged as at 25, and beaded into

the drum 10. Rivets 28, secure the drum to the sheet 5. The space formed at the ends of the tubes by swaging is closed by means of cast iron filler blocks 29. These blocks are split in two halves, and one half has cast 70 therein a bolt, 30, which projects through an opening in the other half, and secures the block in position. The crevice between the body of the tubes I fill by means of a sealing strip, 31. This, as shown in Fig. 8, consists 75 of a strip of tapered or wedge-shaped cross-section, and of substantially the length of the tubes, formed of copper, soft annealed iron, or other suitable material. This strip is inserted between two tubes, and then its 80 thin edge upset with a calking tool, so as to form an effective seal between the tubes, as shown in Fig. 7. I regard this as one of the important features of the invention.

The space between each end tube and the 85 corresponding water leg is filled by means of a cast iron block, 32, preferably divided into two or more sections. This block rests, along one edge, against a series of studs, 35, screwed into the sheet, such as 5, of the 90 water leg, and at its other edge, it is radiused, as shown at 40, so as to conform to the shape of the tube 24, against which it seats. This block is provided on its inner face with a suitable chamber in which is laid 95 fire brick, 33, or some such material, held in place by means of bolts, 34, let into the same, and secured to the block 32. Lugs 37 are carried by said block on its other face, and resting against the two series of lugs 35 and 100 37 is a sealing plate, 38, one edge of which abuts against the wall 5 of the water leg, while the other edge is radiused, and ogeed, as indicated at 41, so as to conform to and fit snugly against the tube, 24, where it is 105 swaged. Bolts 36 extend outwardly from the block 32, and project through the plate 38. As this plate is preferably formed of sheet steel, such as boiler plate, it will be seen that by tightening up the nuts 39, on 110 the bolts 36, the plate 38, which is slightly bowed, or concaved, will have a tendency to straighten and thus elongate, and in so doing, jam between the sheet 5, and the tube 24, thus forming a tight seal. This is 115 necessary in order to prevent the leakage of outside air into the fire-box, and I regard this method of forming a seal as an important feature of my invention.

Referring again to Figs. 1 and 2, 42 represents the usual, or any desired form of grate, supported on an I-beam, 43, secured by means of bolts 44, to a series of brackets 45. These brackets, of which there are preferably six or more, are equally spaced 125 along the side of the lower drums, 10, and secured thereto as by means of stud bolts 46. An angle bar 47, extends the length of the drum, and is securely bolted to the brackets, 45. From the other flange of this bar is 130

supported the usual ash pan, 48, by means of bolts, 49, passing through sleeves, 50. Extending around said drums, 9 and 10, and outer row of tubes, 24, and spaced apart therefrom is a sheathing or casing, 52, serving to cover and hold in position, sectional "magnesia" lagging, 51, or other heat resisting material.

In order to protect the rear wall of the forward water-leg, and, also, to deflect the flame, and cause it to spread through and around the water tubes 24, I arrange a baffle plate, or fire wall, 55, constructed of fire brick, and supported on water tubes, 53, 54, in an inclined position, as shown. All of said tubes extend from the forward water leg, upwardly and backwardly, some of them, as 53, having their upper ends beaded into the drums, 9, while others, as 54, connect with the rear water leg.

While I have thus described my improved boiler fully and in detail, I wish it distinctly understood that I do not limit myself to such exact details, but contemplate the substitution of any and all such mechanical equivalents as may fairly be said to fall within the spirit of the invention, and the scope of the appended claims.

It will thus be seen that I have provided a highly efficient, and economical boiler, having many points of superiority over those now in use, and it is thought that the numerous advantages thereof will be readily appreciated by those skilled in the art.

35 What I claim is:—

1. In a boiler of the locomotive type, having the usual front and rear water legs forming the front and rear walls of the fire-box, combustion chamber, and fire tubes, a pair 40 of upper and a pair of lower water drums extending between the water legs, and a series of tubes connecting the upper drums directly with each other and each drum with the corresponding lower drum, said tubes 45 being set close together, and forming the walls of said fire-box.

2. In a combined water-tube and fire-tube boiler of the locomotive type, front and rear water legs, forming the front and rear walls 50 of the fire-box, a boiler body extending forwardly from said front water leg and having the usual fire-tubes arranged therein, upper and lower water-drums connecting the water legs on each side of the center, a grate supported between the lower drums, and a series 55 of water tubes extending between each upper and lower drum, and set close together, so as to constitute the side walls of the fire-box.

3. In a boiler, front and rear water-legs, 60 and water drums extending therebetween, the rear sheet of said front water-leg being provided with openings formed around their periphery with out-turned flanges adapted to embrace said drums, said sheet be- 65 ing also provided around its edge with a

flange, lapped and riveted to the front sheet of said front water-leg.

4. In a boiler, the combination with a water leg, and water tubes disposed substantially parallel therewith, of a bowed 70 resilient plate, having one edge abutting said water leg, and the opposite edge fitting the adjacent tube, and bolts passing through said plate and so arranged that, when tightened, they tend to straighten the plate and 75 jam the same into close contact with said water leg and tube.

5. In a boiler, a rear water leg, a water drum projecting through the same, a flange turned up from the rear sheet of said water 80 leg and embracing said drum, a ring fitted within the end of the drum adjacent said flange, securing means passing through said flange, drum and ring, and a head for said drum secured to said ring. 85

6. In a boiler, a rear water leg, a water drum projecting through the same and secured thereto, a flanged ring fitted within the end of said drum, and a removable head bolted to said ring, said head, when removed, 90 constituting a man-hole through which access may be had to the interior of said drum.

7. In a boiler, a fire-wall made up of a row of water tubes suitably supported, and a filling between said tubes comprising a malleable, metallic strip inserted between each 95 pair of tubes, and upset.

8. In a boiler, a plurality of tubes, drums into which said tubes are set, and sealing strips of malleable material filling the spaces 100 between adjacent tubes, and distorted in such manner as to be retained in position without fastening means.

9. In a boiler, a pair of tubes, spaced apart, and a filling strip of malleable material for 105 filling the crevice between them, such strip being wedge-shaped in cross-section, and adapted to be inserted between said tubes, and have its thin edge upset so as to hold the strip in position. 110

10. In a boiler, a pair of drums, a plurality of tubes having their ends reduced in diameter and set into said drums, divided filler blocks filling the space between the reduced ends of said tubes, and malleable sealing 115 strips, closing the crevices between the bodies of said tubes.

11. In a boiler, a fire-box, a pair of drums, a row of tubes connecting the same and constituting a wall of the fire-box, a filling closing the crevices between the tubes throughout their whole length, and a fire-proof lagging covering said tubes and drums. 120

12. In a boiler, front and rear water legs, water drums extending therebetween, water 125 tubes connecting said drums and forming a fire-wall, and means closing the space between each end tube, and the corresponding water-leg, such means comprising a filler block having one edge radiused to fit the tube, and 130

having its other edge abutting said water leg, and fire-brick secured to the inside of said filler block.

13. In a boiler, the combination with a water leg, and a row of water tubes extending substantially parallel therewith, of means for closing the space between the end tube and water leg, said means comprising a filler block, a sealing plate overlying said

10 block, and having one edge abutting said

water leg, and the other edge cut to conform to the shape of said tube, and bolts securing said filler block and sealing plate together.

In testimony whereof I affix my signature in presence of two witnesses.

JULIUS KINDERVATER.
